The ornamental design for an adjustable dryer vent positioning bracket, as shown and described.

DESCRIPTION

FIG. 1 is a perspective view of an adjustable dryer vent positioning bracket showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is an isolated view on an enlarged scale taken from FIG. 1 of the adjustable dryer vent positioning bracket.
